UNITED STATES PATENT OFFICE.

ANGELINE E. WAGNER, OF GARY, INDIANA.

HAIR-Straightening DEVICE.

Application filed October 30, 1924. Serial No. 746,783.

To all whom it may concern:

Be it known that I, ANGELINE E. WAGNER, a citizen of the United States, and resident of Gary, in the county of Lake and State of Indiana, have invented certain new and useful Improvements in Hair-Straightening Devices, of which the following is a specification.

My invention relates to hair straightening devices and particularly a device of this character adapted for individual use.

It is the purpose of my present invention to provide a device of this character which can be easily and effectively operated by an individual for the purpose intended, which will be substantially immune against breakage or derangement and which, owing to its simplicity, can be manufactured and sold at an exceedingly small cost.

20 I will describe my invention in the best form known to me at present, but it will be apparent that the same is susceptible to changes in form and proportions and to desirable additions with the exercise of only ordinary mechanical skill and without departing from the scope thereof as set forth in the appended claim.

In the drawings chosen to illustrate my invention

30 Figure 1 is a plan view of my invention; Figure 2, a view similar to Figure 1 looking at the opposite side of the device; and

35 Figure 3, a section on the line 3—3 of Figure 1.

Referring to the drawings my invention is shown as comprising a handle 10, a working head 11 and a stem 12 connecting the head and handle. The head 11 is formed of suitable heat retaining metal and is parallelogrammatic in cross section as clearly shown in Figure 3. Either a solid or hol-

low formation of the head may be resorted to, and in the present instance I show the same as solid. Opposite faces of the head 45 11 are provided respectively with relatively closely spaced transverse grooves 13 and 14 respectively. I construct these grooves so that they increase in depth from one end toward the other end and in this respect the 50 respective sets of grooves are arranged reversely, so as to provide tooth formations 15 and 16 at opposite edges of the head respectively. The stem 12 may also be constructed of metal, while the handle 10 is 55 preferably formed of hard rubber or other suitable substance which is not a good conductor of heat.

In use the head 11 is heated to the desired temperature. The ends of a few strands of hair are grasped in one hand and held substantially horizontal and somewhat taut. The strands thus held are combed on their under sides by the teeth formations 15 and on their upper sides by the teeth formations 60 16. To accomplish the desired purpose another group is treated in a similar manner and so on, care being utilized to maintain the heat at sufficient temperature at all 65 times.

70 I claim:

A comb of the character described including a working head parallelogrammatic in cross section, having grooves formed in and extending the full length of opposite faces 75 thereof to provide teeth, the bases of said grooves being straight and the grooves respectively increasing in depth in opposite directions, being of greatest depth at the acute angular corners of the head. 80

In testimony whereof I hereunto affix my signature.

ANGELINE E. WAGNER.
